UNITED STATES PATENT OFFICE.

FELIX J. MCGUANE, OF CHICAGO, ILLINOIS.

LIQUID-ELEVATOR.

1,221,070.

Specification of Letters Patent.

Patented Apr. 3, 1917.

Application filed October 8, 1915. Serial No. 54,802.

To all whom it may concern:

Be it known that I, FELIX J. MCGUANE, a citizen of the United States, residing at Chicago, in the county of Cook and State 5 of Illinois, have invented a new and useful Liquid-Elevator, of which the following is a specification.

The device forming the subject matter of this application is adapted to be employed 10 for raising water out of a well by air pressure and cross reference is hereby made to my copending application for Letters Patent on a liquid elevator; Serial No. 710,599, filed July 20, 1912, that application showing 15 an elevator embodying many of the principles shown in this application No. 54,802, the claims in the said application No. 710,599 being drawn broadly to cover the construction shown in both of the said applications, 20 and the claims in this application No. 54,802 being drawn to cover features peculiar thereto.

One object of the invention is to improve 25 the shiftable valve structure which, being located in the well, opens and closes to admit water to the action of the air pressure.

A further object of the invention is to provide novel means for controlling the admission of air to the mechanism whereby the 30 valves in the well are shifted.

A further object of the invention is to provide a novel means whereby the actuating mechanism will be under air pressure only when the structure is in operation.

It is within the province of the invention 35 to improve generally and to enhance the utility of devices of that type herein disclosed.

With the above and other objects in view 40 which will appear as the description proceeds, the invention resides in the combination and arrangement of parts and in the details of construction hereinafter described and claimed, it being understood that 45 changes in the precise embodiment of the invention herein disclosed can be made within the scope of what is claimed without departing from the spirit of the invention.

In the accompanying drawings:—

Figure 1 is a vertical sectional view illustrating in its entirety, one form of mechanism embodying the present invention;

Fig. 2 is an elevation showing a portion of the pressure controlled mechanism where-

by the valves in the well are operated; parts 55 being broken away;

Fig. 3 is an elevation of the structure delineated in Fig. 2, the view point in Fig. 3 being 90 degrees remote from the view point in Fig. 2, and parts being broken away; 60

Fig. 4 is a vertical longitudinal section of the mechanism which is located in the well, parts appearing in elevation;

Fig. 5 is a cross section on the line 5—5 of Fig. 4; 65

Fig. 6 is a cross section on the line 6—6 of Fig. 4;

Fig. 7 is a cross section on the line 7—7 of Fig. 4;

Fig. 8 is a vertical sectional detail showing 70 a portion of the mechanism whereby the dash-pot and valve actuating mechanism are operated and controlled;

Fig. 9 is a horizontal section of the structure shown in Fig. 8, the cutting plane being 75 passed above the transverse operative connection between the upright mechanisms shown in Fig. 8;

Fig. 10 is a vertical longitudinal section showing the valve casing which constitutes 80 a part of the air controlled driving mechanism;

Fig. 11 is a vertical sectional view showing a portion of the means whereby the air is automatically cut off when the device is 85 not in use, parts appearing in elevation.

In Fig. 1 of the drawings, the complete device is shown, and it will be understood that Fig. 1 is largely diagrammatic, the view being illustrative merely of one of 90 the many arrangements possible between the various component mechanisms to be described in detail hereinafter.

Regarding Fig. 1 as presenting a typical but not obligatory showing, there appears 95 a chamber 1 defined by a side wall 2, a lower platform 3 and an upper platform 4. The well casing is shown at 50 and extends upwardly to the lower platform 3.

An engine or motor indicated at 5 may 100 be mounted upon the upper platform 4 or elsewhere, the engine 5 being operatively connected in any desired manner with an air compressor 6 of any approved type. An air tank 7 is shown in the present instance 105 as mounted in the chamber 1 and a pipe 8 leads from the compressor 6 to the air tank. In the pipe 8 is interposed a check valve 9

which closes toward the compressor 6, and in the pipe 8 may be placed a hand valve 10.

From the air tank 7, a pipe 11 leads, the pipe 11 carrying a valve 12 which preferably is of the rotary type, the stem of the valve 12 being indicated by the reference character 14. Note Fig. 11. Secured to the stem 14 of the valve 12 is a pinion 15 meshing into a rack 16 formed upon a plunger 17 carrying a weight 18, the plunger being guided in a boss 138 on the top of a tubular casing 19. Located within the casing 19 is an expansible element shown in the form of a bellows 20 with the upper portion of which the lower end of the plunger 17 is connected. In order to support the plunger 17 for right line sliding movement, the casing 19 may be provided with an arm 139 having fingers 140 which span the plunger, there being a roller 141 journaled upon the arm 139 between the fingers 140, the roller 141 receiving one edge of the plunger 17.

The invention includes a tank 22 in the top of which air may be trapped, the lower portion of the tank 22 containing water. A pipe 21 connects the tank 22 with the bellows 20. Entering the tank 22 is a pipe 23 of any desired length, the pipe 23 carrying a faucet or cock 24. It is through the pipe 23 and the faucet 24 that the water from the well 50 ultimately is delivered.

Branched off from the pipe 21 and communicating with the pipe 23 is a pipe 500 in which is interposed a check valve 501 closing toward the bellows-casing 19. Interposed in the pipe 21 and located between the tank 22 and the pipe 500 is a needle valve 502. Located in the pipe 23 upon the opposite side of the tank 22 from the needle valve 502 is a check valve 503 which opens toward the tank 22.

Communicating with the pipe 23 is a pipe 25 in which is interposed a check valve 26. The check valve 26 opens toward the tank 22 and closes in an opposite direction. The pipe 25 constitutes a part of the water delivery system and communicates with a casing denoted generally by the numeral 27 and located in the well tubing 50. The casing 27 is shown in detail in Fig. 4.

The casing 27 as shown in Fig. 4 is a composite structure and includes a base 28 provided with an opening 29 surrounded by a gasket 30 against which abuts a coupling 31, the coupling being held in place by a screw 32 threaded into a bracket 33 forming a part of the base 28. The lower end of the pipe 25 is connected with the coupling 31. Assembled with the base 28 is a tube 34 in which is mounted a thimble 35 having a lateral projection 36 through which leads downwardly a duct 37 for a purpose to be pointed out hereinafter. Located within the thimble 35 is a bushing 38 having a flange 39 which overhangs the upper end of

the thimble 35. Mounted on top of the flange 39 is an abutment ring 40 which may be resilient. Superposed upon the abutment ring 40 is a retaining ring 41, and securing elements 42 pass downwardly through the retaining ring 41, through the abutment 40, through the flange 39 and enter the upper end of the thimble 35. Surrounding the thimble 35 is a tube 43 into which is inserted a strainer head 44 having perforations 45. Surrounding the exterior of the strainer head 44 is a fine meshed screen 46. Mounted in the strainer head 44 is a bushing 47 having a flange 48 which bears upon the lower end of the strainer head. A resilient abutment ring 49 lies against the flange 48, a retaining ring 51 co-operates with the abutment ring, and securing elements 52 unite the parts above mentioned with the strainer head 44.

Mounted to reciprocate in the upper end of the bushing 38 is a lower valve 53 of tubular form, the same being provided in its side wall with ports 54 which taper toward their upper ends. At the upper end of the lower valve 53 there is formed a flange 55 which co-operates with the abutment ring 40 to limit the downward movement of the valve. The space below the valve 53 constitutes a lower chamber 56 and the space above the said valve constitutes an upper chamber 137. Mounted to reciprocate in the bushing 47 is a tubular upper valve 57 having in its side wall, ports 58 which taper toward their lower ends. The upper valve 57 includes a flange 59 which co-operates with the abutment ring 49 to limit the upward movement of the valve. The stem of the lower valve 53 is shown at 60 and is united by means of a ball joint 61 with a connecting rod 62, the upper end of which is united by means of a ball joint 63 with the stem 64 of the upper valve 57, the upper end of the stem 64 being united by a ball joint 65 with a main operating rod 66 which will be alluded to repeatedly hereinafter.

A tube 67 is threaded into or otherwise secured to the upper end of the strainer head 44, the tube 67 passing upwardly through the lower platform 3. Surrounding the tube 67 and vertically adjustable thereon is a base plate 68 held in place by a set screw 69. The base plate 68 co-operates with the lower platform 3 to support the tube 67 and the casing 27 in vertically adjusted positions within the well tubing 50.

The upper end of the tube 67 carries a supporting frame 70 upholding a main cylinder 71 in which reciprocates a main piston 72 secured to the upper end of the main operating rod 66. As clearly shown in Fig. 2, a fulcrum post 74 is pivoted at 73 to the base plate 68, the upper end of the fulcrum post 74 being pivoted as shown at 75 to the intermediate portion of a lever 76 upon one

end of which a weight 77 is adjustable longitudinally of the lever, the weight being held in place by means of a set screw 78. The other end of the lever 76 terminates in 5 spaced fingers 79 which, as shown best in Figs. 8 and 9 span the tube 67. The fingers 79 of the lever 76 engage beneath a cross arm 80 inserted through the main operating rod 66 and held therein by set screws 81, the tube 67 being provided with longitudinal 10 slots 82 in which the cross arm 80 is adapted to reciprocate.

By means of retaining bands 84, a tubular valve casing 83 is attached to the main cylinder 71, the valve casing 83 preferably being open at its ends, wholly or in part as shown in Fig. 10. From the lower end of the valve casing 83 a port pipe 85 leads to the upper portion of the main cylinder 71, and from 15 the top of the valve casing 83, a port pipe 86 leads to the lower portion of the cylinder 71. A stem 87 is mounted to move within the casing 83, the stem carrying an upper valve 88 and lower valve 89.

20 By means of a pivot element 90, the upper end of the valve stem 87 is united with a link 91 having a longitudinal slot 92 in which is mounted to reciprocate a pin 93 which, as shown in Fig. 3, is carried in one end of a 25 walking beam 94 fulcrumed intermediate its ends at 95 upon a standard 96 fixed to and rising from the upper end of the main cylinder 71. Intermediate its ends, the walking beam 94 is provided with an upstanding 30 finger 97 supporting a cross rod 98 to which are attached the upper ends of retractile 35 springs 99, the lower ends of which are connected as shown at 100 to the upper end of the main cylinder 71. That end of the walking beam 94 which is remote from the pin 93 40 carries a pin 101 mounted to move in a slot 102 formed longitudinally in a link 103 pivoted at 104 to the upper end of a combined 45 valve-actuating and dash-pot rod 105 mounted to reciprocate in a guide 106 attached to the main cylinder 71. A dash-pot cylinder 107 is mounted on an arm 108 surrounding the tube 67 and vertically adjustable thereon, the arm 108 being held in place by a set 50 screw 109. Attached to the lower end of the rod 105 is a head 110 adapted to reciprocate in the dash-pot cylinder 107. The lower end of the dash-pot cylinder 107 carries a coupling 111 with which is connected the 55 lower end of a by-pass pipe 112, the upper end of which communicates with the dash-pot cylinder 107 near to the top thereof. The by-pass pipe 112 comprises a filling cup 114 whereby oil or another liquid may be introduced into the dash-pot cylinder 107. Threaded into the coupling 111 is a needle 60 valve 115 co-operating with the lower end of a passage 116 in the coupling 111.

As shown best in Fig. 8, a tube 117 surrounds the dash-pot rod 105, the tube 117, if

desired, being formed in two parts, the adjacent ends of which are threaded into an abutment 118, the abutment 118 thus being fixed upon the tube 117. The abutment 118 is of proper size to pass freely through an 70 opening 119 formed in an extension 120 united by means of securing elements 121 with the cross arm 80, the extension constituting to all intents and purposes, a part of the cross arm. Threaded or otherwise secured on the upper end of the tube 117 is an 75 upper head 122 which, through the medium of a cotter pin or the like, may be connected with the dash-pot rod 105. Interposed between the abutment 118 and the head 122, 80 and movable longitudinally of the tube 117 is an abutment 124 which at times coacts with the fixed abutment 118 and is supported thereby, a compression spring 125 being interposed between the head 122 and the 85 movable abutment 124. An abutment 126 is movable upon the tube 117, longitudinally thereof, the abutment 126 being located below the extension 120 of the cross arm 80. At times, the movable abutment 126 co- 90 operates with the fixed abutment 118, a compression spring 127 being mounted between the abutment 126 and a fixed abutment 128 attached by threading or otherwise to the tube 117, a cotter pin or other suitable connection being employed for uniting the abutment 128 with the dash-pot rod 105. As hereinbefore stated, the abutment 118 is of 95 sufficiently small diameter to pass through the opening 119 in the extension 120 of the 100 cross arm 80. The abutments 124 and 126, however, are sufficiently large in diameter so that they cannot pass through the opening 119.

The lower end of a main air pipe 130 enters the projection 36 of the casing 27 and communicates with the duct 37, a clean-out plug 131 being mounted in the end of the projection 36. The main air pipe 130 communicates with a branch pipe 132 leading to the valve 12. In the branch pipe 132 is placed a hand valve 133, and hand valves 134 and 135 are placed in the main air pipe 130 upon opposite sides of the branch pipe 132. The upper end 136 of the pipe 130 enters the valve casing 83 intermediate its ends as shown most clearly in Figs. 3 and 10.

It will now be pointed out how the water enters the casing 27 of Fig. 4 and is ejected therefrom.

When the main operating rod 66 moves downwardly, the upper valve 57 is unseated and the ports 58 therein are opened. Water thereupon passes downwardly through the strainer head 44 and through the ports 58 into the chamber 137, the lower end of which is closed because the lower valve 53 is seated. During the downward movement of the upper valve 57, air which may have accumulated in the chamber 137 passes upwardly 130

through the ports 58 and out of the strainer head 44. The chamber 137 may now be taken to be filled with water. When the main operating rod 66 moves upwardly, the 5 upper valve 57 is seated, the ports 58 therein being closed. By this same operation, the lower valve 53 is unseated and its ports 54 are opened. Thereupon, the water passes downwardly through the open ports 54 into 10 the lower chamber 56. Air under pressure enters the casing 27 by way of the pipe 130 and the duct 37 and it will now be obvious that if the upper valve 57 is seated as shown in Fig. 4, air accumulating in the chamber 15 137 will force the water out of the pipe 25. If, however, the lower valve 53 is seated, air accumulating in the lower chamber 56 will force the water out through the pipe 25.

The manner of charging the air tank 7 is 20 as follows:—

The valve 133 may be closed if necessary, the valve 10 being opened. The motor or engine 5 is put into operation, driving the air compressor 6, air being forced through 25 the pipe 8 into the tank 7, the function of the check valve 9 with respect to the compressor 6 being obvious. The check valve 26 closes toward the well, and consequently air pressure will be accumulated within the 30 tank 7. When a sufficient pressure in the tank 7 has been attained, the engine 5 is stopped and the valve 10 is closed tightly. If the valve 133 has been closed during the 35 operation above described, the same is now opened.

The weight 18 on the end of the plunger 17 tends to depress the plunger, the rack 16 thereof rotating the stem 14 of the valve 12 through the medium of the pinion 15, the 40 weight 18 acting to maintain the valve open while the water is being drawn off through the pipe 23 and the faucet 24 as will be explained hereinafter.

From the tank 7 air under pressure passes 45 by way of the pipe 11, the pipe 132 and the pipe 130 into the casing 27 through the duct 37 as hereinbefore explained.

From the casing 27 water passes by way 50 of the pipe 25 to the tank 22. If the faucet 24 is closed, that is, during the time that no water is being drawn off, the pressure in the tank 22 rises, a quantity of air normally being trapped in the top of the tank. The pressure thus created is transmitted by way 55 of the pipe 21 into the bellows 20, the latter actuating the plunger 17 which, through the medium of the rack 16 and the pinion 15, closes the valve 12.

It will now be obvious that when the 60 faucet 24 is open, the valve 12 will be opened, thus admitting air under pressure into the casing 27 through the pipes 132 and 130, and by way of the pipe 136 into other elements of the structure, the operations of 65 which will be described hereinafter.

When, however, the faucet 24 is closed, the valve 12 will be closed, and the air supply will be cut off. Therefore, when the structure is not in use there will be no waste of air pressure caused by loose or leaky joints. 70 If, however, a leakage should take place due to imperfect joints, when the structure is in operation, this leakage will be of minor consequence, since the structure is in operation, ordinarily but for a short period, compared 75 with the length of time during which it is not in operation.

A portion of the structure is adapted to secure a positive opening and a tight closing of the valve 12, and to insure that the valve 12 will respond instantly when the faucet 24 is opened. In order that the bellows 20 may relax instantly, the bellows must be drained promptly when the faucet 24 is opened, and the pressure in the tank 22 must be prevented from retarding the collapse of the bellows. In this connection it is to be observed that when the faucet 24 is opened, the water in the bellows 20 flows into the pipe 23 by way of the pipes 21 and 500, but cannot flow 90 in an opposite direction, owing to the presence of the check valve 501 in the pipe 500. Again, the needle valve 502 is so set that the pressure in the tank 22 cannot be communicated rapidly to the bellows 20 while the 95 same is emptying. When the faucet 24 is closed, the needle valve 502 causes the valve 12 to act slowly and the flow of water through the pipe 21 is retarded, and as a consequence, sufficient pressure is stored in 100 the tank 22 so that when the valve 12 does arrive at a closed position, there will be no doubt about its being held closed. If the needle valve 502 did not retard the rush of water to the bellows 24, the valve 12 would 105 cut off the air pressure prematurely without however having effected a complete and tight closure, and if the air were thus cut off, there would not be secured in the tank 22 sufficient pressure to insure a tight closing 110 of the valve 12. The check valve 503 obviously serves to hold the pressure in the tank 22.

When the faucet 24 is opened and the valve 12 is opened, air is delivered into the 115 valve casing 83 intermediate its ends, through the pipe 132, the upper end of the pipe 130, and the lateral extension 136. Presupposing that the valves 88 and 89 occupy the positions shown in Figs. 3 and 10 it will 120 be seen that air under pressure delivered into the casing 83 by way of the pipe 136 will be delivered by means of the port pipe 86 under the main piston 72 on the main operating rod 66, the latter moving upwardly and carrying with it the valves 53 and 57 in the casing 27, as hereinbefore set forth. When the main operation rod 66 moves upwardly, the cross arm 80—120 moves upwardly, the fixed abutment 118 passing through the opening 130

119 and the abutment 124 being engaged by the element 120. The abutment 124 thus is carried upwardly and the spring 125 is compressed, the latter reacting against the head 122 and moving the dash-pot rod 105 upwardly. When the dash-pot rod 105 moves upwardly, the link 103 is carried upwardly, the pin 101 in the walking beam 94 being at the lower end of the slot 102. By this operation, the right hand end of the walking beam 94 (referring to Fig. 3) is raised and the left hand end of the walking beam 94 is depressed. After the upper end of the finger 97 on the walking beam 94 has swung to the left past the vertical, the springs 99 act to depress the left hand end of the walking beam. The pin 93 in the left hand end of the walking beam 94 ultimately arrives at the lower end of the slot 92 in the link 91 and depresses the link 91 along with the valve stem 87. The pin 93, however, does not arrive at the lower end of the slot 92 until after the upper end of the arm 97 on the walking beam 94 has swung to the left, past the vertical, and as a consequence, a dead center is avoided, it being impossible for the valve stem to stop in such a position that the valves 88 and 89 cover the ends of the port pipes 86 and 85.

When valve stem 87 moves downwardly, reference being had particularly to Fig. 10, the lower valve 89 passes below the lower end of the port pipe 85 and air is admitted into top of the cylinder 71 through the pipe 136, the casing 83 and the pipe 85. During this same operation, the upper valve 88 moves below the upper end of the pipe 86 and the exhaust passes out through the open upper end of the casing 83. When the parts are in the positions shown in Fig. 10, the air under pressure is passing beneath the piston 72 by way of the pipe 136, the casing 83 and the pipe 86, the exhaust passing out by way of the pipe 85 and the open lower end of the casing 83.

When the main operating rod 66 moves downwardly, the abutment 118 passes through the opening 119 in the cross arm 120—80, the element 120 engaging the slideable abutment 126 and the spring 127 being put under compression, the latter reacting on the dash-pot rod 105, and an elevation of the left hand end of the walking beam 94 resulting, due to the action of the link 103, in a manner which will be clearly understood from what has been stated hereinbefore.

When the main operating rod 66 moves downwardly, the cross arm 80, coacting with the lever 76, elevates the weight 77 and upon the upstroke of the main operating rod 66 an important assisting action is given by the weight 77, the inertia of the main operating rod 66 and attendant parts being offset to a large extent, upon the upstroke. When the

rod 105 is reciprocated, the head 110 is caused to reciprocate in the dash-pot cylinder 107, the oil or other liquid in the dash-pot cylinder traversing to and fro by way of the by-pass 112. The movement of the rod 105 therefore is retarded and the lineal speed of the rod 105 may be regulated by cutting off the by-pass 112 to a greater or less extent through the medium of the needle valve 115. The rod 105 and connected parts therefore move slowly, but no such movements takes place in the main operating rod 66. An appreciable interval of time elapses between the movements of the rod 66 and when the rod does move, it operates quickly. The valves 57 and 53 therefore move quickly, with an appreciable interval of time between their movement, and it is during this interval that the water enters the casing 27 and fills the chamber 137 as hereinbefore described. The interval during which the valves 53 and 57 remain at rest may be regulated by adjusting the retarding effect of the dash-pot mechanism through the medium of the needle valve 115.

The ball joints, of which the joint 63 may be taken as typical, permit a satisfactory operation of the structure even though the reciprocating elements delineated in Fig. 4 be slightly out of axial alinement.

The check valve 26 prevents the water from running back into the casing 27 through the pipe 25 when the pressure is reduced by the initial opening of the faucet 24.

Having thus described the invention, what is claimed is:—

1. In a device of the class described, a fluid-pressure-actuated liquid-ejecting means embodying a liquid outlet conduit and a fluid pressure inlet conduit; a pressure storage tank in communication with the outlet conduit; an expansible element responsive to a diminution of pressure in the tank; a valve in the inlet conduit; an operative connection between the expansible element and the valve for opening the valve; and a cut-off device in the outlet conduit, the cut-off device being manipulable to permit the passage of liquid through the outlet conduit and to effect a diminution of pressure in the tank.

2. In a device of the class described, a fluid-pressure-actuated liquid-ejecting means embodying a liquid outlet conduit and a fluid-pressure inlet conduit; a rotary valve in the inlet conduit; a pinion operatively connected with the valve, a rack meshing into the pinion; an expansible element connected with the rack; means for establishing a communication between the expansible element and the outlet conduit; and a cut-off device in the outlet conduit.

3. In a device of the class described, a fluid-pressure-actuated liquid-ejecting means embodying a liquid outlet conduit

and a fluid-pressure inlet conduit; a rotary valve in the inlet conduit; a pinion operatively connected with the valve; a rack meshing into the pinion; an expansible element connected with the rack; a tank; means for establishing communication between the tank and the expansible element; means for establishing communication between the tank and the liquid outlet conduit; and a cut-off device in the liquid outlet conduit.

4. In a device of the class described, a fluid-pressure-actuated liquid-ejecting means embodying a liquid outlet conduit and a fluid-pressure inlet conduit; a rotary valve in the inlet conduit; a pinion operatively connected with the valve; a rack meshing into the pinion; a weight carried by the rack; a bellows operatively connected with the rack; a pressure storage tank; a communication between the pressure storage tank and the bellows; means for establishing communication between the storage tank and the liquid outlet conduit; and a cut-off device in the outlet conduit.

5. In a device of the class described, a fluid-pressure-actuated liquid-ejecting means comprising a casing; a fluid-pressure and liquid-controlling valve operating therein; a liquid outlet conduit leading from the casing; a fluid-pressure-actuated means for operating the valve; a fluid-pressure inlet conduit leading to the casing and to said means; an expansion tank communicating with the outlet conduit; a cut-off device in the outlet conduit; an expansible element; a connection between the expansible element and the tank; a valve in the inlet conduit; and means for operatively connecting the last specified valve to the expansible element.

6. In a device of the class described, a fluid-pressure-actuated liquid-ejecting means comprising a casing; a fluid-pressure and liquid-controlling valve therein; a liquid outlet conduit leading from the casing; a cut-off device in the liquid outlet conduit; means for operating the valve; a fluid-pressure inlet conduit leading to the casing and to said means; a rotary valve in the inlet conduit; a pinion operatively connected with the rotary valve; a rack into which the pinion meshes; an expansible element operatively connected with the rack; and a connection between the expansible element and the outlet conduit.

7. In a device of the class described, a fluid-pressure-actuated liquid-ejecting means comprising a casing and a fluid-pressure and liquid-controlling valve therein; a liquid outlet conduit leading from the casing; a cut-off device in the liquid outlet conduit; a fluid-pressure-actuated means for operating the valve; a fluid-pressure conduit leading to the casing and to said means; a

rotary valve in the inlet conduit; a pinion connected with the rotary valve; a rack meshing into the pinion; an expansible element connected with the rack; a pressure storage tank; a connection between the pressure storage tank and the expansible element; and a connection between the pressure storage tank and the liquid outlet conduit.

8. In a device of the class described, a fluid-pressure-actuated liquid-ejecting means comprising a casing; a fluid-pressure and liquid-controlling valve therein; a liquid outlet conduit leading from the casing; a fluid-pressure actuated means for operating the valve; a fluid-pressure inlet conduit leading to the casing and to said means; a rotary valve in the inlet conduit; a pinion connected with the rotary valve; a rack meshing into the pinion; a bellows operatively connected with the rack; a weight carried by the rack; a pressure storage tank; a connection between the pressure storage tank and the bellows; a connection between the pressure storage tank and the liquid outlet conduit; and a cut-off device in the liquid outlet conduit.

9. In a device of the class described, a fluid-pressure-actuated liquid-ejecting means embodying a casing; a fluid-pressure and liquid-controlling valve mounted to reciprocate vertically therein; a liquid outlet conduit leading from the casing; a vertically reciprocating, fluid-pressure-actuated means for operating the valve; a fluid-pressure inlet conduit leading to the casing and to said means; and a counterpoise operatively connected with the fluid-pressure-actuated means.

10. In a device of the class described, a fluid-pressure-actuated liquid-ejecting means embodying a casing; a fluid-pressure and liquid-controlling valve mounted to reciprocate vertically therein; a liquid outlet conduit leading from the casing; a vertically reciprocating, fluid-pressure actuated means for operating the valve; and a fluid-pressure inlet conduit leading to the casing and to said means; a lever; a fulcrum therefor; a weight adjustable along the lever; and an operative connection between the lever and the fluid-pressure-actuated means.

11. In a device of the class described, a casing; a liquid-controlling valve operating therein; a fluid-pressure actuated means for operating the controlling valve; a cut-off valve directing the admission of fluid-pressure to said means; mechanism for moving the cut-off valve; and a yieldable operative connection between said mechanism and the means for operating the controlling valve.

12. In a device of the class described, a casing; a liquid-controlling valve operating therein; a fluid-pressure-actuated means for operating the controlling valve; a cut-off valve directing the admission of the fluid

pressure to the said means; mechanism for moving the cut-off valve; a yieldable operative connection between said mechanism and the means for operating the controlling-
5 valve; and a retarding device operatively connected with the mechanism for moving the cut-off valve.

13. In a device of the class described, a casing; a liquid-controlling valve operating therein; a fluid-pressure-actuated means for operating the controlling valve; a cut-off valve directing the admission of fluid-pressure to said means; mechanism for moving the cut-off valve; a yieldable operative connection between said mechanism and the means for operating the controlling-valve; a retarding device operatively connected with the mechanism for moving the cut-off valve; and means for adjusting the retard-
15 ing action of the retarding device.

14. In a device of the class described, a casing; a liquid-controlling valve operating therein; a fluid-pressure-actuating means for operating the controlling-valve; a cut-off valve directing the admission of fluid-pressure to said means; mechanism for moving the cut-off valves; a yieldable operative connection between said mechanism and the means for operating the controlling-valve,
25 and a dash-pot with which the mechanism for moving the cut-off valve is connected.

15. In a device of the class described, a casing; a liquid-controlling valve operating therein; a fluid-pressure actuated means for operating the controlling-valve; a cut-off valve directing the admission of fluid pressure into said means; mechanism for moving the cut-off valve; a yieldable operative connection between said mechanism and means
35 for operating the controlling-valve; a dash-pot cylinder; a piston working in the dash-pot cylinder and operatively connected with the mechanism for moving the cut-off valve; a by-pass connecting spaced portions of the dash-pot cylinder; and a valve controlling
45 the by-pass.

16. In a device of the class described, a casing; a liquid-controlling-valve operating therein; a fluid-pressure-actuated means for operating the controlling valve; a cut off valve directing the admission of fluid-pressure to said means; a primary mechanism for actuating the cut off valve; a secondary mechanism yieldably connected to the means
50 for operating the controlling valve; and a yieldable operative connection between said primary and secondary mechanisms whereby the primary mechanism will at times be actuated by the secondary mechanism and at times will move independently thereof.

17. In a device of the class described, a casing; a liquid-controlling-valve operating therein; a fluid-pressure-actuated means for operating the controlling valve; a cut off
55 valve directing the admission of fluid-pres-

sure to said means; a rod operatively connected to said valve; a pair of opposed expansible members mounted on said rod and operatively connected thereto; and an operative connection between the aforesaid 70 means for operating the liquid-controlling-valve and the said opposed expansible members whereby motion from said means for operating the liquid-controlling-valve is yieldably transmitted to said rod.

18. In a device of the class described, a casing; a liquid-controlling-valve operating therein; a fluid-pressure-actuated means for operating the controlling valve; a cut off valve directing the admission of fluid pres-
75 sure to said means; a rod operatively connected to said valve; a fixed abutment on the rod; springs surrounding the rod and located on opposite sides of the abutment; the remote ends of the spring being con-
nected with said rod; an arm attached to
80 said means for operating the controlling valve; a ring rigidly attached to the arm and engaging the rod, the fixed abutment on the rod being adapted to pass through 90 the ring, the ring coacting with the adjacent ends of the springs to put the springs alter-
nately under compression.

19. In a device of the class described, a casing; a liquid-controlling valve operating 95 therein; a fluid-pressure cylinder; a piston in the cylinder; a connection between the valve and the piston; a valve directing the admission of fluid-pressure to the cylinder; a projection on the connection; a counter-
100 poise operable by the projection; and an operative connection between the projection and the directing valve.

20. In a device of the class described, a casing; a liquid-controlling valve operating 105 therein; a fluid-pressure cylinder; a piston operating in the cylinder; a connection be-
tween the valve and the piston; a valve directing the admission of fluid - pressure into the cylinder; an arm on the connection; 110 a lever engageable by the arm; a fulcrum for the lever; a weight adjustable along the lever; an operative connection between the arm and the directing valve.

21. In a device of the class described, a 115 casing; a liquid-controlling valve operating therein; a fluid-pressure cylinder; a piston operating in the cylinder; a connection be-
tween the valve and the piston; a valve directing the admission of fluid-pressure 120 into the cylinder; means for operating the directing valve; a counterpoise means; and a single means on the connection for oper-
ating both the counterpoise means and the mechanism for operating the directing 125 valve.

22. In a device of the class described, a casing; a liquid-controlling member operat-
ing therein; a cylinder; a piston working in the cylinder; a connection between the 130

liquid-controlling member and the piston; a valve casing having ports connected with the cylinder; a valve operating in the casing; a walking beam; a support therefor; 5 means for connecting one end of the walking beam with the valve; an actuating element connected with the other end of the walking beam; and interengaging elements on the actuating element and on the connection for operating the actuating member from the connection.

23. In a device of the class described, a casing; a liquid-controlling member operating therein; a cylinder; a piston working 15 in the cylinder; a connection between the liquid-controlling member and the piston; a valve casing having port connection with the cylinder; a valve operating in the valve casing; a walking beam, one end of which is operatively connected with the valve; means for supporting the walking beam; an actuating member connected with the other end of the walking beam; interengaging elements on the actuating member and on the 25 connection for driving the actuating member from the connection; a finger projecting from the walking beam; a spring connected at one end with the finger; and means for fixing the other end of the spring.

30 24. In a device of the class described, a walking beam; a support therefor; an actuating rod; a valve rod; a loose connection between the actuating rod and one end of the walking beam whereby the walking beam 35 will first move with the actuating rod and then move independently of the actuating rod; spring means for moving the walking beam independently of the actuating rod; a loose connection between the other end of the walking beam and the valve rod whereby the walking beam will first move independently of the valve rod under the action of the spring means and then actuate the valve rod; a casing in which the valve rod operates; a cylinder having port connection 45 with the casing; a piston in the cylinder; and a liquid-controlling element operatively connected with the piston.

50 25. In a device of the class described, a walking beam; a support therefor; an actuating rod; a valve rod; links pivoted to the actuating rod and the valve rod; pivot elements upon the walking beam, upon which elements the links are mounted to slide; a 55 casing in which the valve rod operates; a cylinder with which the casing has port connection; a piston operating in the cylinder; spring means for actuating the walking beam independently of the actuating rod; and a liquid-controlling element operatively 60 connected with the piston.

26. In a device of the class described, a

walking beam; a support therefor; a finger upstanding from the walking beam; a retractile spring attached to the finger; means 65 for fixing one end of the spring; links mounted to slide on the walking beam adjacent its ends; an actuating rod connected with one link; a valve rod connected with the other link; a casing in which the valve 70 rod operates; a cylinder having port connection with the casing; a piston working in the cylinder; and a liquid-controlling element operatively connected with the piston.

27. In a device of the class described, a 75 walking beam; a support therefor; a valve casing; a cylinder with which the valve casing has port connection; a valve working in the casing and operatively connected with one end of the walking beam; a rod operatively connected with the other end of the walking beam; a fixed abutment on the rod; springs surrounding the rod and located upon opposite sides of the abutment, the remote ends of the springs being connected 85 with the said rod; a piston working in the cylinder; a liquid-controlling member; a connection between the piston and the liquid-controlling member; an arm on the connection and provided with an opening through 90 which the fixed abutment is adapted to pass, the arm coating with the adjacent ends of the springs to put the springs alternately under compression.

28. In a device of the class described, a 95 fluid-pressure-actuated liquid-ejecting means embodying a liquid outlet conduit and a fluid-pressure inlet conduit; means for opening and closing the liquid outlet conduit; a valve in the inlet conduit; a pressure-storage 100 tank communicating with the outlet conduit; an expansible element in operative connection with the valve in the inlet conduit; a connection between the expansible element and the pressure tank; a bypass connection 105 between the expansible element and the outlet conduit; a controlling valve in the connection between the tank and the expansible element whereby the flow of liquid from the tank to the expansible element can be retarded; means in the bypass connection whereby the backward flow of liquid to the expansible element is prevented; and means in the communicating pipe which connects the tank with the liquid outlet conduit 110 115 whereby the backward flow of liquid from the tank to the outlet conduit is prevented.

In testimony that I claim the foregoing as my own, I have hereto affixed my signature in the presence of two witnesses.

FELIX J. MCGUANE.
